AUGUSTUS J. PENOTE, OF CLEVELAND, OHIO.

FORM FOR CONCRETE STRUCTURES.

1,316,462.

Specification of Letters Patent. Patented Sept. 16, 1919.

Application filed February 4, 1918. Serial No. 215,387.

To all whom it may concern:

Be it known that I, AUGUSTUS J. PENOTE, a citizen of the United States, residing at Cleveland, in the county of Cuyahoga and 5 State of Ohio, have invented a certain new and useful Improvement in Forms for Concrete Structures, of which the following is a full, clear, and exact description.

This invention relates to forms for concrete construction work particularly to rectangular forms adapted especially for making rectangular man-holes such as are employed with underground conduits.

The rectangular forms utilized heretofore for this purpose, have had the very serious disadvantage that they could not be readily removed from the interior of the man-hole after the latter was formed, that is to say, the sections of the form could not be easily withdrawn inwardly so as to permit the removal of the form. The above and other disadvantages of prior forms employed for this purpose are overcome by the present invention which comprises a form composed 25 of any desired number of superposed courses, each of which has its sides and ends formed by matching or inter-fitting sections which can be secured together to form a rigid structure, but have their adjoining ends 30 tapered or beveled in such a way that what may be termed an intermediate section of each side and of each end can be readily moved inward from a concrete structure which has been formed about the form. It 35 is another feature of this invention that in the ordinary use of the form, that is, with the ordinary number of sections, only sections of two different shapes and sizes are required to make up the sides and ends of 40 the form, although the construction is such that by the use of certain filler members to be described, the proportions or size of the form can be readily varied, either increased or decreased.

45 In the accompanying sheet of drawings, Figure 1 is a top plan view of the form, parts being broken away; Fig. 2 is an end view of the form showing three courses; Fig. 3 is a plan view showing three slightly 50 separated sections which make up the major portion of one end and one side of a form; Fig. 4 is a fragmentary view showing the member which is used in the sides of the form in place of what is normally termed 55 the intermediate section, when it is desired to shorten the form in a lengthwise direc-

tion; Fig. 5 is a somewhat similar view showing three of the regular normal sections of the form with another filler member which is adapted to be inserted between the intermediate and one end section of the side, when it is desired to lengthen the form; Fig. 6 is an inner view of a corner section of the form; and Fig. 7 is an inner view of the intermediate section of the form. 60 65

The form embodying my invention may be formed in any number of superposed courses, three courses being shown in Fig. 2, designated A, A' and A'', but the construction of each course is the same as the construction of the other courses, so that when the term "form" is employed it will be understood to apply to one of the courses, or to one unit of a completed form composed of any number of superposed courses. 70 75

In the ordinary use of the form, the latter will be composed of eight separate pieces or sections, including what may be termed four corner sections 10, which are exact counterparts or duplicates of each other, and four 80 intermediate sections 11 which are exact counterparts or duplicates of each other, one intermediate section being adapted to be inserted in each side, and one in each end between the corner sections. 85

Each corner section or part consists of an upper horizontal strip 10^a, a lower horizontal strip 10^b, a vertical end piece 10^c, a second vertical end piece 10^d, these four parts forming a rectangular frame, and in addition a 90 side or facing 10^e, whose outer face is smooth and is adapted to form a bearing for the concrete of the structure which is to be built around the form, this structure being a rectangular man-hole in the ordinary use of the 95 form.

Each intermediate section 11 includes an upper horizontal strip 11^a, a lower horizontal strip 11^b, two vertical end strips 11^c and 11^d, together with the outer side or facing 11^e. 100

The terms "horizontal" and "vertical" are used for convenience in description for the reason that the parts to which these words are applied, have that relationship when the form is in actual use, or is assembled for use, and is in normal position. It may be stated further at this point, that the parts 10 and 11 are all preferably formed of wood, as this material is best adapted to this use for many reasons, although any other materials 110 which answer the requirements may be employed.

Considering now the detailed construction of the corner sections 10, it will be observed that the vertical piece 10^c is set at an acute angle with respect to the outer side 5 or facing 10^e, and that at the opposite end of the section 10 there is a right angle corner, a short section of the facing 10^f similar to, but at right angles to the side or facing 10^e being located at the end of the section 10. The second vertical piece 10^d is also inclined, making the same acute angle with the facing 10^f as the vertical piece 10^c makes with the facing 10^e. As before stated, all four corner sections 10 are constructed precisely alike.

The intermediate section 11 of the form has both vertical members 11^c and 11^d inclined with respect to the side or facing 11^e, both said vertical members making an obtuse angle with respect to the facing 11^e which is the complement of the acute angle which the members 10^c and 11^d of the corner section 10 make with the facings 10^e and 10^f respectively.

25 It will be seen therefore that when the sections of the form are assembled in their normal relationship, the intermediate sections 11 constitute wedge-shaped sections, one of which is set into each side between the outwardly converging ends of the long portions of two corner sections, and one between the outwardly converging ends of the relatively short portions of the corner sections. When the parts are thus assembled, the vertical end pieces 11^c and 11^d of each intermediate section lie flatly against the adjacent vertical members of the corner sections. The parts are preferably held in this position with the outer sides or facings 30 forming a substantially perfect rectangle by means of short bolts 12 which extend through each pair of engaging vertical members of each pair of adjoining intermediate and corner sections.

40 It will be obvious from the construction above described, that when the concrete structure has been formed about the form, it will be a comparatively simple matter to remove the form, for when the bolts 12 are 45 removed, the four intermediate sections can be separated from the four corner sections by simply pulling them inwardly from between the ends of the corner sections. Not only does the form have the advantage 50 above stated, but by reason of the fact that the corner sections are all precisely alike and the intermediate sections of both sides and ends of the form are exactly similar in construction, the form can be very readily 55 placed together for there will be eliminated the necessity of carefully selecting and matching the parts which are placed in contiguous relationship.

As many courses as are required may be

placed on the lowermost course, and the 65 different courses can be held in precise alignment by pins 13 driven through openings 14, properly located in the horizontal members of the intermediate and corner sections, the openings in corresponding superposed 70 parts of any two courses being in alignment so that when the pins 13 are driven into place, the outer sides or facings of all superposed courses will be in the same vertical planes.

75 The above construction is such that the dimensions of the form can be readily increased or decreased if circumstances require. For example, if it is desired to increase the length or width of the form, this 80 can be done by the use of filler members 15 which may be inserted between the intermediate and corner sections in the sides or ends of the form, these filler members 15 having parallel sides as shown in Fig. 3. 85 On the other hand, if it is desired to shorten the form, by a given amount, this can be done by eliminating the intermediate sections 11 in the sides, and inserting in place, wedge-shaped fillers 16, shown in Fig. 4, so 90 as to close the V-shaped gap between the adjacent ends of the corner sections. These 95 filler members 15 or 16 can be secured in place, that is, can be secured to the members they engage by screws or bolts.

In practice the uppermost course will be provided with a roof or covering generally formed by laying boards thereon, and this covering will be provided with an opening of any desired size and shape adapted to 100 permit entrance to the man-hole or structure which is formed of concrete or similar material around the form.

105 Thus it will be seen that by this construction the advantages previously enumerated are attained, but while I have shown only the preferred form, it will be apparent that changes may be made in details of construction, and I aim in my claims to cover all 110 modifications which do not involve a departure from the spirit and scope of my invention in its broadest aspects.

Having described my invention, I claim:

115 1. A rectangular form for concrete construction work composed of four counterpart corner sections and four counterpart intermediate sections, each intermediate section comprising an outer side, upper and lower members, and two end members which are inclined with respect to the outer side 120 and making equal obtuse angles therewith, each corner section comprising a relatively long outer side, a relatively short outer side making a right angle with the first-named, top and bottom members, and two end members which are inclined with respect to, and make acute angles with the relatively long 125 and the relatively short outer sides of the

- corner section, said acute angles being complements of the obtuse angles which the end members of the intermediate section make with the outer side thereof, whereby when 5 the sections are assembled with an intermediate section between each pair of corner sections, said end members of the intermediate and corner sections are parallel and in engagement.
- 10 2. A rectangular form for concrete construction work composed of four counterpart corner sections and four counterpart intermediate sections, each intermediate section comprising an outer side, upper and 15 lower members, and two end members which are inclined with respect to the outer side and making equal obtuse angles therewith, each corner section comprising a relatively long outer side, a relatively short outer side 20 making a right angle with the first-named, top and bottom members, and two end members which are inclined with respect to, and make acute angles with the relatively long and the relatively short outer sides of the 25 corner section, said acute angles being complements of the obtuse angles which the end members of the intermediate section make with the outer side thereof, whereby when the sections are assembled with an intermediate section between each pair of corner sections, adjacent end members of the intermediate and corner sections are parallel and in engagement, and means for fastening the 30 sections together comprising fastening devices extending through engaging end members of the intermediate and corner sections. 35
3. A rectangular form for concrete construction work composed of four counterpart corner sections and four counterpart intermediate sections, each intermediate section comprising an outer side, upper and lower members, and two end members which are inclined with respect to the outer side and making equal obtuse angles therewith, each corner section comprising a relatively long outer side, a relatively short outer side 40 making a right angle with the first-named, top and bottom members, and two end members which are inclined with respect to, and make acute angles with the relatively long outer side and the relatively short outer sides of the corner section, said acute angles being complements of the obtuse angles which the end members of the intermediate section make with the outer side thereof, whereby when 45 the sections are assembled with an intermediate section between each pair of corner sections, said end members of the intermediate and corner sections are parallel and in engagement, the top and bottom members of 50 the sections forming supports and engaging portions for superimposed courses of forms above specified, said top and bottom members being provided with openings adapted to receive fastening devices. 55
